UNITED STATES PATENT OFFICE.

HENRY ANTOINE LEFEVRE, OF PARIS, FRANCE.

HEAT-ENGINE.

1,234,184.

Specification of Letters Patent. Patented July 24, 1917.

Application filed March 27, 1917. Serial No. 157,811.

To all whom it may concern:

Be it known that I, HENRY ANTOINE LEFEVRE, a citizen of the United States of America, residing at Paris, France, have invented new and useful Improvements in Heat-Engines, of which the following is a specification.

In order to increase the duty of heat engines, it is usual to heat the compressed-air 10 motor-cylinders in such a manner as to obtain a better utilization of this air.

In practice this superheating is limited by the fact that the best oils for lubricating the pistons and the motor-cylinders burn when 15 they are raised to a temperature above about 250 degrees C.

On the other hand, when the superheating reaches a somewhat high degree, it produces during the admission period a premature expansion of the compressed air, which expands in the valve chest and admission-ports, which causes a part of the benefit of superheating the air during its expansion in the cylinder to be lost.

25 The present invention has for its object improvements in heat engines, having for their object to enable the superheating of the air during its expansion to be increased at will without having to fear injury to the 30 pistons and cylinders and of avoiding the premature expansion of the compressed air while it is being admitted into the motor-cylinders.

These improvements consist essentially:

35 1. In thermally insulating the upper part of the cylinder where the compressed air is admitted; the capacity of the part of the cylinder thus insulated corresponding to the weight of air that should normally be admitted into this cylinder.

40 2. In thermally insulating the part of the cylinder around which the hot fluid circulates, and in dividing the piston into two parts which are also thermally insulated 45 from one another, the part of this piston working in the superheated part of the cylinder and in the upper insulated part of the latter being of a diameter less than that of the cylinder-bore.

50 By this arrangement, the temperature of the air can be raised to a degree much higher than with the arrangements heretofore usual, since a part of the lubricant can be dispensed with in the superheated part of the engine 55 by reason of the annular space left between

the cylinder and the piston, and on the other hand, the premature expansion of the air is no longer to be feared since the upper part of the cylinder where the admission takes place is insulated thermally in such a manner that 60 its temperature is not greater than that of the air at the moment of such admission.

The invention is shown by way of example in the accompanying drawing, wherein:

Figure 1 shows in vertical section a heat 65 engine, of which the superheated part of the cylinder is insulated thermally from the rest of said cylinder.

Fig. 2 also shows in vertical section an engine, the upper and lower parts of which are 70 insulated thermally.

As shown in Fig. 1 of the drawing, the cylinder of the engine is divided transversely into two parts; a lower part *a* connected to the gear-case *b* and in which the 75 piston moves in the usual manner, and an upper part *a'* insulated thermally from the first by a joint *c* of any suitable material.

Around this upper part of the cylinder, there is arranged an annular chamber *d* in 80 which circulates a hot fluid such as the exhaust gases from a petrol or gas engine, or a liquid raised to a high temperature, etc.

In the cylinder so arranged, there moves a piston also divided into two parts: a lower 85 part *e* connected by a rod *f* to the engine-shaft *g*, and an upper part or false piston *e'* insulated thermally from the piston proper *e* by a disk *h* of insulating material.

The false piston *e'* alone works in the upper superheated part *a'* of the cylinder and the diameter of this false piston is less than that of the bore of the cylinder so that an annular space is left between the two parts, such space permitting the employment 95 of a lubricant between them to be dispensed with.

By this arrangement, only the upper part *a'* of the cylinder will be raised to a high temperature by the superheated fluid circulating in the chamber *d*, and only the false piston *e'* moving without lubricant in this upper part of the cylinder will be subjected to the action of the heat.

Under these conditions, it is possible to 105 raise the temperature of the upper part *a'* of the cylinder as desired and consequently that of the internal air without interfering with the efficient operation of the lower cylinder *a* and of the piston proper *e*.

In order to avoid premature expansion of the compressed air admitted into the cylinder, the upper part of the cylinder is also insulated thermally by a joint *i* of insulating material from the part *a'* of the cylinder around which circulates the hot fluid.

The cylinder is thus divided transversely into three parts *a*, *a'* and *a²* insulated thermally from each other by the joints *c* and *i* as shown in Fig. 2.

10 Into the upper part *a²* of the cylinder there opens the admission port *j* for compressed air. The internal dimensions of this part *a²* of the cylinder correspond to the 15 weight of the air which should normally be admitted at each cylinder-charge.

20 The false piston *e'* carried by the piston *e* and separated from the latter by the insulating joint *h*, is of a diameter less than that of the bore of the cylinder in order to permit the use of lubricant to be dispensed with, as has been explained above. The height 25 of this false piston is such that it comes, at the end of its stroke, into the upper part *a²* of the cylinder.

30 By this arrangement, although the temperature of the superheating fluid can be raised at will, the compressed air at the moment of its admission into the cylinder will not be raised in temperature so as to 35 effect its premature expansion, since all the air necessary for a cylinder-charge is admitted into the part *a²* of the engine, which is insulated thermally from the rest of the latter and of which the temperature is not greater than that of the air at the moment of its admission.

40 Under these conditions, my improved engine enables a maximum weight of air to be admitted for each cylinder-charge, which in conjunction with the high temperature to which it is then submitted, insures complete expansion of this air in the cylinder and perfect operation of the engine.

45 As mentioned above, the insulating joints *c*, *h* and *i* can be of any suitable material. The effect of these joints can be regulated by suitably varying their thickness.

50 The present invention can also be applied to all types of heat engines, more especially to explosion-engines, for the purpose above specified.

55 The above arrangements are only given by way of example, the forms, dimensions and detail arrangements can be varied according to particular cases without departing from the nature of the invention.

What I claim is:

1. In a heat engine the combination of a cylinder consisting of two parts, a heat insulator between said parts, a piston fitting one of said parts, a false piston operating in the other part and having a diameter less than the interior diameter of said other part, means for thermally insulating said false piston from said piston, and means for superheating that part only of the cylinder which contains said false piston. 60 65

2. In a heat engine the combination of a cylinder, means for superheating a part of said cylinder, means for admitting the charge into the outer end of said cylinder, and means for thermally insulating said superheated part and outer end for preventing the premature expansion of the charge during its admission. 70 75

3. In a heat engine the combination of a cylinder divided transversely into three parts which are thermally insulated from one another, an annular chamber for the 80 passage of superheating fluid surrounding the median part of the cylinder, means for admitting compressed air to the outer end of the cylinder and a joint of a material that is a non-conductor of heat interposed between the superheated part of the cylinder and said outer end of the latter in order to avoid the premature expansion of the air during its admission. 85

4. In a heat engine the combination of a cylinder divided transversely into three parts that are thermally insulated from one another, an annular chamber for the passage of the superheating fluid surrounding the median part of the cylinder, means for admitting compressed air to the outer end of the cylinder, a joint of a material that is a non-conductor of heat interposed between the superheated part of the cylinder and the 95 said outer end of the latter in order to avoid the premature expansion of this air during its period of admission, a piston moving in the inner end of the cylinder, a false piston fixed to said piston and of a diameter less than that of the bore of the cylinder 100 such false piston extending into the superheated part of the cylinder and into the said outer end of the latter, and a joint of a material that is a non-conductor of heat interposed between the piston and the false piston. 105 110

HENRY ANTOINE LEFEVRE.
